UNITED STATES PATENT OFFICE.

G. M. WOOD, OF DECATUR, ILLINOIS.

IMPROVED KEEPER FOR BOLTS.

Specification forming part of Letters Patent No. 58,929, dated October 16, 1866.

To all whom it may concern:

Be it known that I, G. M. WOOD, of Decatur, in the county of Macon and State of Illinois, have invented a new and useful Improvement in Keepers for Bolts; and I do hereby declare that the following is a full, clear, and exact description thereof, which will enable others skilled in the art to make and use the same, reference being had to the accompanying drawing, forming part of this specification.

The drawing represents a front or face view of my invention.

The object of this invention is to obviate the difficulty attending the sagging of doors, shutters, &c., to which bolts are attached. When a bolt is first applied to a new door and the keeper secured in line with it on the door-frame, the keeper will, of course, receive the bolt; but all new wood will eventually shrink more or less, and the door sag in a greater or less degree, and frequently to such an extent that the bolt cannot enter the keeper.

My invention consists in having the keeper formed with oblong slots for the screws which secure the keeper in position to pass through, and which admit of the keeper being adjusted to compensate for shrinkage and the sagging of the door.

In the accompanying drawing, A represents

the keeper of an ordinary slide-bolt. Slide-bolts are not generally affected by shrinkage of the wood, as they have a considerable length of movement to admit of them entering the keeper, even if the door and door-frame should shrink very materially; but they are very frequently rendered useless or inoperative by the sagging of the door, and hence I construct keepers for this purpose with vertical slots *a a* for the screws *b* to pass through, to secure it to the door-frame. These vertical oblong slots admit of the keeper being adjusted downward in case the door to which the bolt is attached sags, and hence the keeper may always be kept in line with the bolt.

The adjustment of the keeper, in event of the contingencies specified, is shown in red.

Having thus described my invention, I claim as new and desire to secure by Letters Patent—

The providing of the keepers of bolts with oblong screw-slots, in the manner substantially as and for the purpose set forth.

The above specification of my invention signed by me this 24th day of April, 1866.

G. M. WOOD.
